UNITED STATES PATENT OFFICE

160,085

HEATER FOR BOX TOE BLANKS AND THE LIKE

Raymond B. Harrison, Braintree, Mass., assignor
to Beckwith Manufacturing Company, Dover,
N. H., a corporation of New Hampshire

Application September 6, 1947, Serial No. 141,235

Term of patent 14 years

(Cl. D81—10)

To all whom it may concern:

Be it known that I, Raymond B. Harrison, a citizen of the United States and a resident of Braintree, in the county of Norfolk and Commonwealth of Massachusetts, have invented a new, original, and ornamental Design for a Heater for Box Toe Blanks and the like, of which the following is a specification, reference being had to the accompanying drawing, forming a part thereof, in which the figure is a view in perspective of a heater for box toe blanks and the like, showing my new design.

The side and back of the heater not shown in the figure are substantially plain.

The dominant features of my design reside in the portions shown in full lines.

I claim:

The ornamental design for a heater for box toe blanks and the like, as shown and described.

RAYMOND B. HARRISON.
